UNITED STATES PATENT OFFICE.

JOSHUA J. NIX AND WARREN J. FROST, OF LOS ANGELES, CALIFORNIA; SAID NIX ASSIGNOR
TO SAID FROST.

APPARATUS FOR PRODUCING GAS.

No. 900,010.

Specification of Letters Patent.

Patented Sept. 29, 1908.

Application filed February 18, 1907. Serial No. 358,152.

To all whom it may concern:

Be it known that we, JOSHUA J. NIX and WARREN H. FROST, citizens of the United States, residing at Los Angeles, in the county of Los Angeles and State of California, have invented a new and useful Apparatus for Producing Gas, of which the following is a specification.

This invention relates particularly to the production of gas for use in internal combustion engines, although the gas may be used for other purposes.

The main object of the present invention is to produce gas from hydrocarbon oils in a continuous manner by internal combustion.

Another object of the present invention is to dispense with the necessity of any storage tanks.

Another object of the invention is to provide for the production of gas of uniform quality or composition.

Another object of the invention is to provide for the production of gas having a larger proportion of fixed hydrocarbon gases than is the case with ordinary producer gas.

Another object of the invention is to provide for automatic regulation of the gas production for fluctuations in the demand.

The present process is distinguished from those processes using retorts, in that the heat for production and fixation of the gas is generated internally, that is to say, in the same chamber or space which contains the hydrocarbon to be gasified, so that the heat does not have to be transmitted through the walls.

Said retort processes are not suitable for the production of gas from heavy hydrocarbons, in that the accumulation of residuum and deposits interferes seriously with the continuity

and economy of the process and with the uniformity of the gas, and also in that the expense of such production is prohibitive.

The process of the present invention is also distinguished from those processes involving internal combustion intermittently with the gas generation, the heat being applied to and stored in a chamber or body and the generation of the heat being then stopped and shifted to another point and the gas being

generated by applying the oil to the chamber or body so heated. In this intermittent or alternate process the quality of the gas necessarily varies during each stage, as the temperature of the chamber or heating body

rapidly falls and the character of the gener-

ated gas varies with the falling temperature. This variation is equalized in practice by the use of storage tanks or gasometers in which the varying constituents are allowed to mix before consumption.

The present invention provides for a continuous generation at uniform temperature and thereby produces gas of uniform quality or composition and dispenses with the necessity of any storage tank means.

According to the present invention gas is generated by passing the oil, or the vapor formed by atomizing oil, into or through a heating zone which is kept continuously at a high temperature by supplementary heating means or burners, the reaction or mutual action of the oil and of the gaseous contents of the heating zone being such as to produce a permanent gas. These operations are performed in a chamber which is open to communication with the outer air, and is connected at its upper portion to a suction means continuously drawing the produced gas from the chamber.

In the accompanying drawings:—Figure 1 is a vertical section of the apparatus partly in elevation. Fig. 2 is a horizontal section on the line x^2-x^3 in Fig. 1. Fig. 3 is a section on the line x^3-x^3 in Fig. 1. Fig. 4 is a side elevation. Fig. 5 is a detail side elevation of the generator feed or supply. Fig. 6 is an end elevation thereof. Fig. 7 is a front elevation of the heating burner. Fig. 8 is a horizontal section thereof.

The apparatus comprises a furnace or generator 1 preferably formed of masonry or other heat-resisting material and formed with an interior vertical chamber 2 and a flue 3 leading upwardly therefrom to a discharge outlet at the top into an outlet conduit 4, having an upwardly inclined extension 5 into a stack 6. Said stack is provided with a closure valve 7, and an aspirator 8 is connected to the stack or to the outlet flue 5 to draw the gas therefrom into delivery pipe 12, as hereinafter set forth, said aspirator being actuated by water supplied by pipe 9.

Heating burners 10, of which there may be any desired number, are provided, discharging inwardly into the chamber 2, said burners being provided with air and oil supply means, as hereinafter set forth, and having outlet means or jet pieces 11, whose openings are directed obliquely downward

toward the center of the chamber 2 so that the jets issuing from said openings will meet in the interior of the chamber 2. The walls of the generator are formed with passages 5 13 extending inwardly from these heating burners to the chamber 2 to permit of the passage of the jets therefrom to the chamber. The burners or the adjacent portions of the chamber walls are formed with openings 44, for the admission of air, so that 10 the chamber is open to communication with the outer air. The burners 10 discharge into the chamber 2 near enough to the bottom thereof to keep the bottom well heated, 15 avoiding deposition of carbon thereon.

Means are provided for supplying oil, or a mixture of oil and air suitable for the gas to be produced, below the flame or flames from the burner or burners 10, said means 20 consisting of an inlet pipe 15 extending through the wall of the generator and connected to an oil feed as hereinafter described, to furnish a supply of atomized oil, together with air, to the lower part of the 25 chamber 2. The said supply means for this outlet, shown in Figs. 5 and 6, comprises an oil supply pipe 17, a chambered fitting 18 connected to said oil supply pipe by a connecting member 19, a glass or transparent 30 tube 20 connecting said oil supply pipe with the chamber 21 in said fitting so as to produce a sight feed for the supply, and an air supply pipe 22 having a nozzle 23 extending into said chamber to produce an injector 35 effect therein, the walls of said chamber being narrower at 24 to accentuate said injector effect and cause the mixture of air and atomized oil to pass into the inlet pipe 15.

The upper portion of chamber 2 preferably converges upward to its outlet into flue 3, and said flue may be swelled or enlarged to form a supplementary chamber and may be provided with baffles in the form of checker work or fire brick obstructions 25 45 extending across the same to deflect the upwardly passing gases and cause more thorough mixture.

26 designates a door, plug or other means in the wall for giving access to the chamber 50 2 in starting up, etc.

In order to heat the oil before it passes to the burners and also in order to cause preliminary separation of the oil, as far as possible, in the manner hereinafter set forth, the 55 tank 27 for containing the oil supply is placed on or near the generator or furnace in such position as to receive the heat therefrom, for example, being placed thereon around the outlet flue 4, so that the hot gases pass upwardly through said flue and heat said tank. 60 28 designates the oil supply pipe to this oil tank and 53 a plug for drawing off residuum.

29 designates the oil outlet pipe leading from the lower part of the tank through pipes 65 30 and valves 31 to the heating burners 10.

A pipe 34 leads from the upper part of the tank 27 to the supply 17 for the generator burner, and is provided with a valve 36 operated by connections 37 from a governor 38 on the engine 39 which is supplied with gas 70 from the producer. A connection 56 is made from the delivery pipe 12 through suitable scrubbing means 57, see Fig. 4, to the inlet 55 for the engine. A manual valve may also be provided for the oil supply. The 75 connections 37 may also operate a valve 33 controlling the air supply to the mixture inlet. The suction of the engine 39 at each intake stroke tends to draw the gas through the connections between the producer and 80 the engine through the scrubber, not shown, and thereby aids in maintaining the passage or supply of air and combustible to the gas generating chamber. The air supplied to the heating burners is preferably heated by 85 the exhaust from said engine, pipe 32 for said air supply passing around said exhaust and communicating through the valve 40 with pipe 42 for the said burners. This air is supplied at a considerable pressure generated by any suitable means, such as a pump 90 not shown.

While various forms of heating burners may be used in connection with the apparatus, that shown in Figs. 7 and 8 is especially 95 designed for this purpose, the burner head 11 being attached to a plate 43 secured to the wall of the generator chamber, said plate having openings 44 for the passage of air extending obliquely therethrough so as to converge toward the burner jet opening 45 which is formed in a head or nozzle 11 projecting from the base of a conical depression 46 in said plate. Damper means consisting of a plate 47 is adjustably secured on the supporting plate 43 by means of screws 48 extending through slots 49 on said damper plate, the said damper plate having perforations 50 to register more or less with the openings 44 in the supporting plate. In order to enable 100 quick adjustment, for example, on stopping the engine, means are provided for indicating accurately the degree of opening of the damper, such means consisting of an index or pointer 51 on the damper moving over a 115 fixed graduated scale 52. Pipe 42 opens laterally into an outer pipe 54 screwing onto the outer end of burner nozzle 11. Said nozzle has a bore 55 smaller than pipe 54. The oil supply pipe 29 extends into the end 120 of pipe 54 beyond the opening of pipe 42.

The process is carried out in the above described apparatus as follows:—Closure or valve 7 in the stack is opened and the heating burners 10 are turned on and ignited, the jets 125 in said burners extending into the chamber 2, heating the same, and the hot gases passing up through the flue 3 and out through the stack. When the chamber 2 has thus become thoroughly heated, the damper 7 in the 130

stack is closed, the aspirator 8 is turned on so as to draw the gases downwardly through the delivery pipe 12 to any suitable consumption means, for example, the engine 39, or 5 service pipes not shown; and the valves 40, 31 for the mixture or producing supply means are turned on, causing a supply of atomized oil together with just sufficient air to carry the same is thereby blown into the 10 lower part of the chamber 2. The two jets from the opposite burners 10 meet in the middle of the furnace, and by their impingement and opposition mutually arrest each other and produce a zone or layer of intensely heated gases extending across the 15 chamber at a level between the lower and upper portions thereof and above the intake of the producing mixture. The mixture is applied under the pressure of, say 20 pounds to 20 the square inch, and the same is true of the oil, and this together with the suction by the aspirator and the suction of the engine or consuming means, causes a flow of the producing mixture upwardly through or into 25 this high temperature zone. The chamber 2 is open to the outer air through the openings 44, and the air compressed and forced in with the oil is not sufficient to support combustion, the oil so carried in burning in the open 30 chamber and the combustion being supported by the air passing through openings 44. We thus insure complete combustion of the oil and maximum temperature of the heating flame, without compression of more than a 35 small part of the air and with a correspondingly great economy. The suction of the products of combustion, from the top of the chamber, by the engine and the aspirator, keeps the products of combustion away from 40 the incoming combustible and air, thus aiding in maintaining perfect combustion at the heating burners. The condition of suction maintained in the chamber is also of advantage, as compared with a condition of pressure, for mechanical reasons, in preventing 45 leakage and reducing the strains on the parts of the furnace.

In the above described construction the interior of the chamber is clear or free of solid 50 obstructions, such as brick or checkwork, in the path of the jets. Consequently there is no liability of deposition of carbon on solid surfaces. This is further insured by the fact that each of the heating jets is impinged by 55 an opposing elastic fluid jet (namely, the other burner jet) which arrests it in the interior of the chamber, and prevents it from impinging on the opposite wall. The vertical disposition of the chamber is also of importance in this connection as it permits of 60 the jets being arranged in this manner.

The baffle devices 25 in the outlet flue are for the purpose of insuring more thorough mixture of the gases and complete combustion. By proper adjustment of the heat-

ing burners and producing inlet valves, it is possible to maintain continuity of the process for an almost indefinite length of time, producing gas of uniform quality ready for instant delivery to the service or consumption means without having to be stored or mixed. For this reason and also for the very fact that the process is continuous, the capacity of the plant is large compared with one of the same size using the intermittent process.

It will be noted that the oil is supplied to the oil tank at a point between the upper and lower portions thereof and that the outlet to the heating burners is from the lower portion, and the outlet to the producing inlet is from the upper portion. When oils of high gravity are heated, there is a tendency for the heavier constituents to settle and these will pass down to the heating burners, whereas the more volatile constituents will have a tendency to pass through the upper outlet and thence to the producing inlet. This is of advantage in that the heating burners are more capable of utilizing the heavier constituents, whereas such constituents could not be utilized in the producing inlet, as they could not be satisfactorily atomized in the manner required. Any volatile constituents of the oil will pass off at the top along with the lighter oil and will form part of the producing mixture. Actual residuum which is not suitable for burning, collects in the oil tank 22 below the outlet to the heating burner and may be drawn off from time to time by the plug 53.

In case of fluctuating demand, means are provided for varying the gas production in correspondence with the fluctuations. This is necessary for the reason that this invention dispenses with the use of a storage tank and therefore it is necessary to cut down or increase the supply in response to the diminishing or increasing demand. For example, in case of a producer used in connection with a gas engine, it is necessary to reduce or increase the supply in accordance with the demands of the engine, and for this purpose the connection from the engine governor to the oil supply for the producing inlet is provided as above described.

The upwardly inclined extension 5 of the outlet, leading to the stack, is found to be essential to securing the proper draft, both in starting the draft into the stack and in maintaining it by the aspirator.

When the producer is used in connection with a gas engine we prefer to make the capacity of the chamber 2 correspond, roughly speaking, to the capacity of the engine cylinder, the throat or outlet portion 3 being in that case of such size as to represent the volume of the valve passages, etc. Thus at each operation enough mixture is drawn through and formed into gas to charge the cylinder.

What we claim is:—

1. An apparatus for producing gas from liquid hydrocarbons, comprising a vertical chamber open to communication with the outer air, burner means adjacent to the bottom of the chamber to heat the same internally, means for admitting hydrocarbon to the chamber between the bottom of the chamber and the heating burners and suction means connected to the upper part of the chamber to withdraw gas therefrom. 70
2. An apparatus for producing gas from liquid hydrocarbons, comprising a chamber open to communication with the outer air, near the bottom of the chamber, provided with means for projecting a flame downward to thereby heat the chamber internally, means for admitting hydrocarbon to the chamber between the bottom of the chamber and the jet from the burner means, and means for continual suction of gas from the chamber, above the jet from the burner means. 75
3. An apparatus for producing gas from liquid hydrocarbons, comprising a chamber, burner means communicating with the chamber to heat the same internally, inwardly converging air inlets surrounding said burner means and communicating with the outer air, means for injecting hydrocarbon with an elastic compressed fluid to the chamber below the jet from the burner means, and means for continual suction of gas from the chamber, above the jet from the burner means. 80
4. An apparatus for producing gas from liquid hydrocarbons, comprising a chamber open to communication with the outer air, burners extending oppositely to direct into said chamber, downwardly extending jets which impinge on one another adjacent to the bottom, means for admitting hydrocarbon to the chamber between said bottom and the said jets, and means for continuously drawing off gas from the chamber above the said jets. 85
5. An apparatus for producing gas from liquid hydrocarbons, comprising a chamber open to communication with the outer air, burner means communicating with the chamber, the interior of the chamber being clear of solid obstructions in the path of the jets from said burner means, means for opposing an elastic fluid jet, to the jet from the burner means, means for supplying hydrocarbon, with an elastic fluid, to the chamber, below the said jets, and suction means connected to the chamber above the said jets, to draw off the gases from the upper part of the chamber. 90
6. A gas generator comprising a chamber, a burner communicating into said chamber to generate a zone of high temperature gases, and means for supplying hydrocarbon to the chamber below the said zone, the said chamber being unobstructed between the levels of said burner and hydrocarbon supply means and having an outlet above the said zone and means for continuously withdrawing gas from said outlet. 95
7. An apparatus for producing gas from heavy hydrocarbons, comprising means for separating the heavier from the lighter portion of the hydrocarbon, means for burning the heavier portion of the hydrocarbon to form a zone of gases at high temperature, and means for passing the lighter portion of the hydrocarbon into and through such zone. 100
8. An apparatus for the production of gas from hydrocarbons, comprising a chamber, burner means extending into communication with the chamber to generate in the chamber a zone of high temperature gases, producing inlet means opening into the chamber to direct thereinto beneath the said zone, a mixture containing the liquid hydrocarbon with an elastic fluid carrier medium therefor, the chamber being open to communication with the outer air and being free from obstructions between the burner means and the producing inlet means, and delivery means for conveying the produced gases from above the said zone, comprising a flue above the chamber having refractory baffle means and provided with an outlet. 105
9. An apparatus for the production of gas from hydrocarbons, comprising a chamber, burner means extending into communication with the chamber to generate in the chamber a zone of high temperature gases, producing inlet means opening into the chamber to direct thereinto beneath the said zone, a mixture containing the liquid hydrocarbon with an elastic fluid carrier medium therefor, an oil supply tank, the chamber having outlet means passing in heating relation to the oil tank to heat the oil therein and pipes connecting the said tank with the burners and with the hydrocarbon supply for the producer, and delivery means for conveying the produced gases from above the said zone. 110
10. An apparatus for the production of gas from hydrocarbons, comprising a chamber, burner means extending into communication with the chamber to generate in the chamber a zone of high temperature gases, producing inlet means opening into the chamber to direct thereinto beneath the said zone, a mixture containing the liquid hydrocarbon with an elastic fluid carrier medium therefor, an oil supply tank, the chamber having outlet means passing in heating relation to the oil tank to heat the oil therein and pipes connecting the said tank with the burners for heating the chamber and with the hydrocarbon supply for the producer, and delivery means for conveying the produced gases from above the said zone. 115
11. An apparatus for the production of gas from hydrocarbons, comprising a chamber, 120

burner means extending into communication with the chamber to generate in the chamber a zone of high temperature gases, producing inlet means opening into the chamber to direct thereto, beneath the said zone, a mixture containing the liquid hydrocarbons with an elastic fluid carrier medium therefor, an oil supply tank, the chamber having outlet means passing in heating relation to the oil tank to heat the oil therein and pipes connecting the lower part of the said tank with the burners and the upper part of said tank with the hydrocarbon supply for the producer, delivery means for conveying the produced gases from above the said zone, and an oil inlet to the tank between such upper and lower parts.

12. A gas generator comprising a chamber, means for continuously supplying air thereto at substantially atmospheric pressure, burner means for continuously producing a zone of high temperature in the chamber, means for continuously supplying combustible to the chamber with an elastic fluid medium to continuously generate gas therein at high temperature, said chamber having an outlet for such gas, a gas engine, connections between said outlet and the gas engine whereby the gas generator supplies the gas for the engine, and the suction of the engine aids in maintaining the passage of air and combustible through the chamber, a governor operated by the engine and means operated by the governor for regulating the supply of combustible admitted to the chamber of the generator according to the demands of the engine.

13. A gas generator comprising a chamber, means for continuously supplying air thereto at substantially atmospheric pressure, burner means for continuously producing a zone of high temperature in the chamber, means for continuously supplying combustible to the chamber with an elastic fluid medium to continuously generate gas therein at high temperature, said chamber having an outlet for such gas, a gas engine, connections between such outlet and the gas engine whereby the gas generator supplies the gas for the engine, and the suction of the engine aids in maintaining the passage of air and combustible through the chamber, an exhauster in the connections between the chamber and the engine to provide for continual exhaust from the chamber, a governor operated by the engine and means operated by the governor for regulating the supply of combustible admitted to the chamber of the generator according to the demands of the engine.

14. A gas generator comprising a chamber, means for continuously supplying air thereto at substantially atmospheric pressure, burner means for continuously producing a zone of high temperature in the chamber,

ber, means for continuously supplying combustible to the chamber with an elastic fluid medium to continuously generate gas therein at high temperature, said chamber having an outlet for such gas, a gas engine, connections between such outlet and the gas engine whereby the gas generator supplies the gas for the engine, and the suction of the engine aids in maintaining the passage of air and combustible through the chamber, an exhauster in the connections between the chamber and the engine to provide for continual exhaust from the chamber, a scrubber in said connections, a governor operated by the engine and means operated by the governor for regulating the supply of combustible admitted to the chamber of the generator, according to the demands of the engine.

15. A gas generator comprising a chamber, means for continuously supplying air thereto at substantially atmospheric pressure, burner means for continuously producing a zone of high temperature in the chamber, means for continuously supplying combustible to the chamber with an elastic fluid medium to continuously generate gas therein to produce a zone of high temperature, and an inlet for supply of hydrocarbon with expansive fluid, below said zone, the chamber being unobstructed between the levels of said burners and inlet, said chamber having an outlet for the gas above said burners, a gas engine, and connections between said outlet and the gas engine whereby the gas generator supplies the gas for the engine, and the suction of the engine aids in maintaining the passage of air and combustible through the chamber.

16. A gas generator comprising a chamber, means for continuously supplying air thereto at substantially atmospheric pressure, burner means for continuously producing a zone of high temperature in the chamber, means for continuously supplying combustible to the chamber with an elastic fluid medium to continuously generate gas therein to produce a zone of high temperature, and an inlet for supply of hydrocarbon with expansive fluid, below said zone, the chamber being unobstructed between said burners and inlet, said chamber having an outlet for the gas above said burner, a gas engine, connections between said outlet and the gas engine whereby the gas generator supplies the gas for the engine, and the suction of the engine aids in maintaining the passage of air and combustible through the chamber, a governor operated by the engine and means operated by the governor for regulating the supply of combustible admitted to the chamber of the generator, according to the demands of the engine.

17. A gas generator comprising a chamber, means for continuously supplying air

65 130

thereto at substantially atmospheric pressure, burner means for continuously producing a zone of high temperature in the chamber, means for continuously supplying combustible to the chamber with an elastic fluid medium to continuously generate gas therein at high temperature, said means comprising opposing burners each impinging its jet on that of the other burner, to produce a zone of high temperature, and an inlet for supply of hydrocarbon with expansive fluid, below said zone, the chamber being unobstructed between said burners and inlet, said chamber having an outlet for the gas above said burners, a gas engine, connections between said outlet and the gas engine whereby the gas generator supplies the gas for the engine, and the suction of the engine aids in maintaining the passage of air and combustible through the chamber, a governor operated by the engine, means operated by the governor for regulating the supply of combustible admitted to the chamber of the generator, according to the demands of the engine, and an exhauster connected to the outlet from the chamber to continuously exhaust the gas therefrom.

18. A gas generator comprising a chamber, means for continuously supplying air thereto at substantially atmospheric pressure, burner means for continuously producing a zone of high temperature in the chamber, means for continuously supplying

combustible to the chamber with an elastic fluid medium to continuously generate gas therein at high temperature, said means comprising opposing burners each impinging its jet on that of the other burner, to produce a zone of high temperature, and an inlet for supply of hydrocarbon with expansive fluid, below said zone, the chamber being unobstructed between said burners and inlet, said chamber having an outlet for the gas above said burners, a gas engine, connections between said outlet and the gas engine whereby the gas generator supplies the gas for the engine, and the suction of the engine aids in maintaining the passage of air and combustible through the chamber, a governor operated by the engine, means operated by the governor for regulating the supply of combustible admitted to the chamber of the generator, according to the demands of the engine, an exhauster connected to the outlet from the chamber to continuously exhaust the gas therefrom, and a scrubber in the connections between the generator and the engine.

In testimony whereof, we have hereunto set our hands at Los Angeles, California, this 28th day of January, 1907.

JOSHUA J. NIX.
WARREN H. FROST.

In presence of—

ARTHUR P. KNIGHT,
FRANK L. A. GRAHAM.
